United States Patent Office

Des. 187,342
Patented Mar. 1, 1960

187,342

ELECTRONIC ORGAN

William Zaiser, Rockville Centre, N.Y., assignor to The Wurlitzer Company, North Tonawanda, N.Y., a corporation of Ohio

Application July 2, 1958, Serial No. 51,626

Term of patent 14 years

(Cl. D56—2)

The single figure is a perspective view of an electronic organ, showing my new design.

I claim:

The ornamental design for an electronic organ, substantially as shown.
